UNITED STATES PATENT OFFICE

WILLIAM DAVEY, OF CLEVELAND, OHIO

DEVICE FOR RECUTTING VALVE SEATS

Application filed March 18, 1929. Serial No. 348,021.

This invention relates to devices for recutting valve-seats, and has for its objects to provide a simple and convenient device with a novel feeding device, and also being 5 adapted to receive centering or anchoring devices of different sizes and shapes, easily-operated and adapted to be quickly and easily applied to faucets, ball-cocks and valve casings and the like of various shapes and 10 sizes, and through the instrumentalities of the same, the valve-seat therein may be perfectly recut with a level seat, and with but a minimum amount of effort.

In the accompanying drawings is shown 15 an example of my invention.

Figure 1 being a sectional central elevation of the device.

Figure 2 is a side view of the device at right angles to the view shown in Fig. 1, 20 with the frusto-conoidal body member reversed thereon.

Like numbers refer to like parts in all of the figures. In said drawings 1 indicates a frusto-conoidal body member having an 25 axial threaded bore 2, and having an integral diaphragm 3 closely engaging the tool shaft to centralize and guide the same, and also having external threads 4 and internal threads 5 and also having a portion exteriorly threaded as at 6.

The foundation unit A is provided on its lower side with an integrally formed annular retaining wall 7, this wall is internally threaded as at 8 or otherwise, and adapted 35 to reversibly receive the threaded portion 6 of the frusto-conoidal body member which is externally threaded to fit the threaded portion of the retaining wall. The boss 9 is concentric with the annular retaining wall 40 on the base plate B, and integrally formed therewith and is exteriorly threaded as at 10, and provided with an axial bore 11, the threaded portion 2 of the body member is adapted to screw onto this boss, thus providing a means to secure the frusto-conoidal body member to the unit as shown in Figure 2. The upper side of the foundation unit is provided with integrally formed sections 12; 12, and having connected thereto 45 a top boss 13, integral with the sections, but

separated from the unit and forming with the unit a receiving opening 14. The unit is centrally socketed as at 15 for the reception of a helical expansion spring 16 coiled about the tool shaft and interposed between 55 the bottom wall 17 of the socket which serves as a seat for the lower extremity of the spring and a movable securing means to yieldingly hold the latter against a non-rotatable tubular element or sleeve member 60 mounted on the top boss. The top boss is exteriorly threaded as at 18, being adapted to engage a similarly threaded feeding device 19 mounted thereon. The non-rotatable tubular element 20 is formed with openings 21; 21 at its diametrically opposite sides, in alignment with, and of the same width as the sections on the foundation unit. The securing means 22 is mounted in the receiving opening, adjustably, and on the 70 tool shaft and provided with a lock screw 23 and an axial bore 24. The securing means is socketed on its underneath side as at 25 to receive the upper extremity of the helical expansion spring, and on its upper side as at 75 26 to receive the lower extremity of the non-rotatable sleeve member mounted on the top boss and interposed between the feeding device and the securing means. 27 indicates the upper, and 28 the lower wall of the receiving opening. The lock screw permits the securing means to be adjusted at a predetermined point on the tool shaft. The non-rotatable sleeve member is employed to prevent the feeding device from having self 80 loosening movement when the tool shaft is moved by the operator in a counterclockwise direction in the mechanism illustrated and also serves as regards adjustment cooperating with the feeding device and the securing 85 means. The helical expansion spring is employed to return the securing means to the top wall of the receiving opening when it has reached the lower wall of same through adjustment, and also to yieldingly hold the securing means against the non-rotatable sleeve member. By unscrewing the feeding device 90 the spring forces the securing means upwards carrying with it at the same time the sleeve member on the top boss. 29 indicates 95 100

the tool shaft, having at its upper end an actuating means 30 and at its lower end a removably mounted cutter 32, having a number or equi- or other suitably spaced cutting edges 33. By the method shown it is possible to utilize frusto conoidal members of different sizes and shapes without materially altering the parts of the foundation unit. It will be noted that the foundation unit is bodily removable from the remainder of the device, and may be used independently thereof. The foundation unit is shown as being integrally formed but may be of composite form. By the means outlined there is ample pressure available through the feeding device for retaining the cutter in the desired cutting relation with the valve seat with certainty and reliability. It will be readily understood that repairs and replacement can be readily had by reason of the ability to disconnect the various parts, and that a variety of frusto conoidal members of various angularity, or in other words the frusto-conoidal member may be steeply or slightly tapered as desired, and may be mounted thereon and employed according to the character of the valve casing in which the valve seat is to be cut. The unit may be constructed of any suitable metal, such as iron, steel or brass or a combination of one or both of these metals, or of any other metal usually employed in the art and is not, therefore, described in detail. In the practical use of the device, the body member is screwed upon or into the body portion of the casting of the valve, faucet or ball-cock from which the valve stem and cap have been removed, the locking device released in the securing means mounted on the tool shaft, then the tool shaft with its cutter is forced down in the device until the cutter engages the valve seat, the securing means is then locked on the shaft, and rotated clockwise; if necessary to change the position of the cutter relative to the valve seat, the feeding device is turned downward on the top boss, and the cutter again revolved, the operation is repeated until desired results have been obtained. In this manner the seat is recut quickly, effecting a large economy.

The embodiments of the invention illustrated and described herein have been selected for the purpose of clearly setting forth the principles involved. It will be apparent, however that the invention is susceptible of being modified to meet the different conditions encountered in its use and I therefore aim to cover by the appended claims all modifications within the true spirit and scope of my invention.

What is claimed is:—

1. A device of the class described comprising a foundation unit with a socket therein, and also having a receiving opening in it, said unit having an integral threaded

boss with an axial bore therethrough at its upper end, and an integral threaded centrally located boss with an axial bore therethrough located on the lower end of the foundation unit and also an interiorly threaded retaining wall at its lower end, an adjustable socketed securing means adjustably mounted in the receiving opening, and having an axial bore therethrough and also having a threaded set screw for a locking device mounted therein, a non-rotatable sleeve member vertically movably mounted on the upper boss and engaging the socket in the securing means, a feeding device threadedly engaging the upper boss, an expansion spring mounted in the socket in the foundation unit and engaging the socket in the securing means, an internally and externally threaded frusto-conoidal body member having an integral diaphragm formed therein and detachably secured to the foundation unit, and a slidably and rotatably mounted tool shaft extending axially through said device and having an actuating means on its upper end and a detachably mounted cutter on its lower end.

2. A device of the class described comprising a foundation unit having a receiving opening in it, said unit having an integral threaded boss with an axial bore therethrough at its upper end, and an integral threaded centrally located boss with an axial bore therethrough at its lower end, an adjustable securing means adjustably mounted in the receiving opening, and having an axial bore therethrough and also having a threaded locking device mounted therein and mounted on the tool shaft, a non-rotatable sleeve member movably mounted on the upper boss and contacting with the securing means, a feeding device threadedly engaging the upper boss, a conical spiral spring interposed between the underneath side of the securing means and the lower wall of the receiving opening, an internally threaded frusto-conoidal body member having an integral diaphragm formed therein removably secured to the boss on the foundation unit, and a slidably and rotatably mounted tool shaft extending axially through said device having an actuating means on its upper end and a removably mounted cutter having a plurality of cutting edges across its flat face and also circumferentially equi spaced cutting edges, on its lower end.

3. A device of the class described comprising a foundation unit with a socket therein, and also having a receiving opening in it, said unit having an integral threaded boss with an axial bore therethrough at its upper end, an interiorly threaded retaining wall at its lower end, an adjustable socketed securing means adjustably mounted in the receiving opening, and having an axial bore therethrough and also having a threaded locking

device mounted therein, a non-rotatable sleeve member vertically movably mounted on the upper boss and engaging the socket in the securing means, a feeding device 5 threadedly engaging the upper boss, an expansion spring mounted in the socket in the foundation unit and engaging the socket in the securing means, an externally threaded frusto-conoidal body member having a portion 10 exteriorly threaded engaging the threaded portion of the retaining wall, an integral diaphragm formed in said body member adapted to centralize and guide a tool shaft, the tool shaft extending axially through said device and having an actuating means on its upper end and a detachably mounted cutter on its lower end.

4. A device of the class described comprising a foundation unit having a receiving 20 opening in it, said unit having an integral threaded boss with an axial bore therethrough at its upper end, and an integral threaded centrally located boss with an axial bore therethrough at its lower end, a securing 25 means adjustably mounted in the receiving opening, and having an axial bore therethrough and also having a threaded locking device mounted therein, a non-rotatable sleeve member vertically movably mounted 30 on the upper boss, a feeding device threadedly engaging the upper boss, an expansion spring interposed between the underneath side of the securing means and the lower wall of the receiving opening, an externally 35 threaded frusto-conoidal body member having an axial bore adapted to engage a tool shaft, the upper end of said bore being enlarged and interiorly threaded adapted to screw onto the centrally located threaded 40 boss on the foundation unit, and a vertically slidable and rotatably mounted tool shaft 45 extending axially through said device and having an actuating means on its upper end and a removably mounted cutter on its lower end.

5. In a device of the class described comprising a frusto-conoidal member externally threaded and having an axial bore and a socket therein and having sections integrally 50 formed and connected therewith and forming therewith a receiving opening and having an integral threaded boss with an axial bore therethrough above said receiving opening the bore in said boss being in axial alignment with the bore in the frusto-conoidal body member, an adjustable socketed securing means adjustably mounted in the receiving 55 opening, and having an axial bore therethrough and a threaded locking device 60 mounted therein, a non-rotatable sleeve member having formed therein openings at its diametrically opposite sides, in alignment with, and of the same width as the sections, an expansion spring mounted in the socket 65 frusto-conoidal member and engaging the

socket in the securing means, and a slidably and rotatably mounted tool shaft extending axially through said device and having an actuating means on its upper end and a detachably secured cutter on its lower end. 70

6. A device of the class described comprising a foundation unit having a receiving opening in it, said unit having an integral interiorly-threaded boss at its upper end, an interiorly threaded retaining wall at its lower end, an adjustable socketed securing means adjustably mounted in the receiving opening, and having an axial bore therethrough and a threaded locking means mounted therein, a vertically movably sleeve member mounted in the interiorly-threaded boss at the upper end, said sleeve member having an axial bore closely engaging the tool shaft, its lower end engaging in the socket in the securing means, a feeding device 75 threadedly engaging the interiorly-threaded upper boss, an expansion spring 80 interposed between the lower wall of the foundation unit and the underneath side of the securing means and having its upper extremity mounted in the socket therein, a cylindrical body member having an interiorly-threaded portion and being of such internal cross-sectional configuration to produce a greater width at the bottom than the 85 top, said body member having a portion exteriorly threaded adapted to threadedly engage the threaded retaining wall on the foundation unit, and a slidably and rotatably mounted tool shaft extending axially 90 through said device and having an actuating means on its upper end and a detachably mounted cutter having radially-extending 95 cutters on its flat cutting face and circumferentially-disposed cutting edges around its 100 periphery. 105

7. A device of the class described comprising a cylindrical body member having an interiorly tapered and threaded portion, oppositely disposed sections integral with said body member, a threaded boss integral with the sections and having an axial bore therethrough, and forming with the body member a receiving opening, an adjustable securing means adjustably mounted in the receiving opening, and having an axial bore therethrough and a threaded locking means mounted therein, a non-rotatable sleeve member mounted on the boss and engaging the securing means, a feeding device threadedly engaging the boss, an expansion spring 110 interposed between the body member and the securing means, the base member having an axial bore closely engaging a tool shaft adjacent the lower extremity of the expansion spring, and a slidably and rotatably mounted tool shaft extending axially 115 through the said boss, securing means and body of said device and having on its upper end an actuating means detachably secured, 120 125 130

and on its lower end a removably mounted cutter having cutters which biases the valve seat in the direction of cutting rotation.

8. A device of the class described comprising a foundation unit having a receiving opening in it, said unit having an integral exteriorly threaded boss at its upper end, and also an interiorly threaded retaining wall at its lower end, an adjustable securing means adjustably mounted in the receiving opening, and having an axial bore therethrough and a threaded locking device mounted therein, a feeding device threadedly engaging the upper boss and having an axial bore therethrough closely engaging a tool shaft and engaging the securing means, an expansion spring mounted on the tool shaft and interposed between the under side of the securing means and the lower wall of the receiving opening; a body member of composite form comprising a two-diameter cylindrical body member having two portions detachably threaded together, axially aligned, the larger of the two cylindrical portions threadedly engaging the threaded retaining wall of the foundation unit, the smaller cylindrical portion threadedly engaging the larger cylindrical portion, each of said cylindrical portions being provided with an individual tapered and threaded inner bore, the said bore in the smaller cylindrical portion being steeply tapered, the said bore in the larger cylindrical portion being slightly tapered, and a slidably and rotatably mounted tool shaft extending axially through said device and having an actuating means on its upper end and a detachably mounted cutter on its lower end.

In testimony whereof, I hereunto affix my signature.

40 WILLIAM DAVEY.
